CLAIM

The ornamental design for a shoe, as shown and described.

DESCRIPTION

FIG. 1 is a front perspective view of the shoe.

FIG. 2 is a rear perspective view of the shoe.

FIG. 3 is a right elevation of the shoe.

FIG. 4 is a left elevation of the shoe.

FIG. 5 is a front elevation of the shoe.

FIG. 6 is a rear elevation of the shoe.

FIG. 7 is a top plan view of the shoe; and,

FIG. 8 is a bottom plan view of the shoe.

The shoe depicted is a right shoe, the design includes a left shoe, being a mirror image thereof.

The broken lines in the drawings represent unclaimed subject matter and form no part of the claimed design.
